Attn: S.

UNITED STATES PATENT OFFICE.

JOSEPH BECKER, OF PITTSBURGH, PENNSYLVANIA, ASSIGNOR TO THE KOPPERS COMPANY, OF PITTSBURGH, PENNSYLVANIA, A CORPORATION OF PENNSYLVANIA.

COKING RETORT OVEN.

Application filed March 14, 1921. Serial No. 452,238.

This invention comprehends improvements of general utility in the coking retort oven art; and also comprehends certain improvements especially applicable to coking retort ovens of the well known cross-regenerative type, exemplified in the patent to H. Koppers, No. 818,033, dated April 17, 1906.

The invention has for objects the provision of a coking retort oven provided with a double series of flues in its heating walls, and having, as important characteristics: A flue construction that permits a considerable reduction not only in the length but also in the cross-sectional dimensions of the horizontal or bus flues located at the top of the vertical flame flues, and connecting a plurality of the latter with each other; and, as a feature that may be secured by the above structural improvements, a novel system of control of the flow through the double series of flame flues of the heating walls, permitting flow in the same direction through all the flame flues of both series of each heating wall, with the result that all the flame flues of each heating wall are either simultaneously burning or simultaneously operating as outflow flues for carrying away the waste gases to outflow operating regenerators.

With regard to the novel flue construction, for example, a pair of horizontal flues for each series of flame flues in each heating wall may be substituted for the usual single horizontal flue which extends from end to end of the heating wall. With the separate horizontal flues, each member of each pair need communicate with only approximately half the total number of flues of each series, and consequently the dimensions of each flue may be considerably decreased because of the consequent reduction in the volume of flow which must be maintained through the horizontal flues. The above stated reduction in size of the horizontal flues is an important advantage, for the reason that it enables a considerable thickening and strengthening of the walls of the oven structure in the region of the horizontal flues. Moreover, the improved flue construction permits an increase in the height of the flame flues, with a corresponding increase in the height of the coking

chambers, so that the latter may be made narrower in width, a development greatly facilitating the coking of high volatile coals, and yet having adequate provision for taking care of the increased volume of combustion products, without making it necessary to enlarge the horizontal flue dimensions to sizes inconsistent with adequate strength of the wall construction in the region of such flues. The flue construction of the invention is furthermore of great importance in oven batteries fired with extraneously derived gas, such as producer gas, since the employment of such gas results in an increased volume of combustion products and consequently flue spaces must be provided to collect and feed to the operating down-flow flues this increased volume of combustion products. By the invention, the flue construction may be adequately accommodated to such increased volume of combustion products, without introducing elements of weakness in the wall structure.

In addition to the objects recited above, the invention comprehends a novel regenerator construction, a system of flow therethrough and through the flues, promoting uniformity of distribution, and has for other objects such other improvements or advantages in construction and operation as are found to obtain in the structures and devices hereinafter described or claimed.

In the accompanying drawings, forming a part of this specification and showing, for purposes of exemplification, a preferred form and manner in which the invention may be embodied and practised, but without limiting the claimed invention to such illustrative instance or instances:

Figure 1 is a crosswise vertical section through a coke oven battery embodying features above specified and equipped with the improvements of the present invention, the view being taken longitudinally through a coking chamber and a pair of regenerators, in planes indicated by the line A—A of Fig. 2;

Figure 2 is a composite vertical sectional elevation taken longitudinally of a coke oven battery, in planes indicated by the lines D—D, E—E and G—G of Fig. 3;

Figure 3 is a vertical section taken transversely through the coke oven battery and

longitudinally through a heating wall, in a plane indicated by the line C—C of Fig. 2; and

Figure 4 is a horizontal sectional elevation through a heating wall taken in a plane indicated by the line H—H of Fig. 2.

The same characters of reference designate the same parts in each of the several views of the drawings.

- 10 In the embodiment illustrated in the drawings, the invention is incorporated in a combination coke oven battery, i. e., a battery having provision for being operated either with producer gas as fuel or with the 15 coke oven gas that is derived from the distillation of the coal in the coking chambers of the battery. For convenience, the present description will be confined to the present illustrated embodiment of the invention 20 in such a combination coke oven battery; the novel features and improvements, made by the invention, are susceptible of other applications, such, for example, as in ordinary so-called "coke ovens" employing coke oven 25 gas as fuel, or ordinary so-called "gas ovens" employing producer gas as fuel; hence, the scope of the invention is not confined to the specific use and specific embodiment herein described as an illustrative example.
- 30 Referring to the drawings, there are illustrated views of a coke oven battery or plant of the by-product type, having features above specified; said battery embodies in its construction a plurality of crosswise 35 elongated heating walls 11, 11, and a plurality of intermediate crosswise elongated vertical coking chambers 12, 12. The heating walls 11 form the side walls of the respective coking chambers 12, as shown more 40 particularly in Fig. 2, and, in the present instance, are directly supported by the heavy supporting or pillar walls 13, 13, which extend crosswise of the battery and are located, as shown in Fig. 2, in pairs beneath the respective heating walls 11, 11. These pillar walls, together with other walls hereinafter described, collectively form the main support for the entire superstructure of the oven battery, and are themselves supported 45 upon a flat mat or platform which constitutes the subfoundation on which the entire battery rests.
- 50

The coal to be coked is charged into the several coking chambers or ovens through charging holes 14 located in the top 15 of the oven battery and positioned directly above the ovens or chambers 12, as shown in Figs. 1 and 2. These charging holes 14 are equipped with the usual removable covers, which are removed during charging of the individual ovens or coking chambers and are placed in position to close the tops of such coking chambers during the entire coking or distilling operation. The gases of distillation pass from the tops of the several

coking chambers 12 through gas outlets 16, and thence through ascension pipes (not shown) into the usual gas collecting main, which carries the distillation products to the by-product recovery apparatus.

70

Heat for coking the charges of fuel in the several ovens or chambers 12 is derived from the heating walls 11, which, as before mentioned, extend crosswise of the battery at the sides of the coking chambers. Referring 75 now more particularly to Figs. 2, 3 and 4, each heating wall 11 is constituted of two parallel series, G and H, of flame or combustion flues 17. Each series of such flame flues extends from end to end of the heating wall and, in accordance with the invention, all of the flues of both series of a heating wall operate concurrently for flow in the same direction, while, at the same time, all of the flues of both series of an adjacent 80 heating wall are operated concurrently for flow in the opposite direction. That is to say, the flame flues of each heating wall are, although in two series, operatively disposed in a single group. When the flame flues 85 on one side of a coking chamber are burning, or operating for upflow, the flame flues on the opposite side of the same coking chamber are operating for downflow to permit exhaust of the waste gases. Consequently, 90 heating is maintained continuously from end to end on one side of a charge of coal in each coking chamber, the heat being applied to the full length of one side of such charge during an entire period, and then, 95 after reversal, being applied to the full length of the opposite side of the charge until a subsequent reversal is effected.

100

The crosswise regenerators 18 of the retort oven or battery are located below the 105 aforesaid heating walls 11 and coking chambers 12, and, in the present instance, extend in parallelism between the pillar walls 13 and the other heavy supporting walls hereinafter described. Located in the lengthwise middle plane of the coke oven battery is a vertical partition 19, as shown in Fig. 1, which partition extends all the way up from the mat of the battery to the bottom of the overlying coking chamber, and from one 110 to the other of the pillar walls 13 and the other walls which are between some of the pillar walls. The regenerators, which are respectively located on opposite sides of the battery, extend inwardly to said partition 115 19 and are separated thereby, as clearly shown in Fig. 1. This arrangement permits control from opposite sides of the battery of the flow through the regenerators, thereby assisting the novel flue arrangement in promoting uniformity of distribution.

120

125 Each regenerator 18 is a chamber containing open brickwork, commonly called checkerwork and indicated at 20, with a distributing sole channel 21 underneath such 130

checkerwork, the channels forming the soles of such chambers and opening up into the checkerwork. In accordance with the invention, a heavy vertical gas-tight supporting wall 22 extends directly beneath each coking chamber 12 in parallelism between the side faces of alternate pillar walls 13, and such supporting walls 22 form the divisions between the groups of regenerators which are respectively companioned to the heating walls. For convenience, the inflow groups of regenerators of one reversal period are designated by the reference character K and the outflow groups of regenerators by the reference character L, the inflow groups alternating with the outflow groups, as shown in Fig. 2. The several walls 22 also have the function, with the pillar walls 13, of supporting the weight of the battery superstructure.

This supporting wall construction provides a pair of crosswise-extending, parallel, gas-tight, load-carrying walls located beneath each heating wall and a supporting wall 22 directly beneath each coking chamber. The walls 22, which are beneath the coking chambers, are constructed and function, not as mere partitions commonly employed, but as true load-carrying, gas-tight walls, permitting relatively different pressures to be maintained in the checkerwork chambers on the opposite sides of such walls, or the flow of different media in the checkerwork chambers separated by these walls, without leakages from one checkerwork chamber into another or without danger of mixing the gases in the checkerwork chambers, which must be kept separate in this region of the battery.

The regenerators of each group, K and L, are heated, in alternation, by the hot combustion products that draw off from the flame or combustion flues hereinbefore mentioned, and then impart such heat to the medium which they feed into these flame flues; in the present instance, the flow through the groups K, L, located on opposite sides of a supporting wall 22, is maintained concurrently in opposite directions; for example, when the flow is passing up through the regenerators of the group K, downflow is being maintained concurrently through the regenerators of the group L. Each group K, L, of such regenerators comprises a central regenerator P, as viewed in Fig. 2, and two side regenerators A, the central regenerator P, when operating for inflow, during producer gas operation, serving to convey producer or other extraneously derived fuel gas to the flame flues of both series G and H, and the side regenerators A respectively serving, on inflow, to direct air to the flues of the series G and H of the adjacent heating wall. The regenerators A of each group are provided with a series of

ducts, 23, which lead respectively to individual flame flues 17 of both series G and H of the same heating wall; each regenerator P is provided with two series of ducts, 24 and 25, one series 24 leading into the flame flues of the series G and the other series of ducts 25 leading into the flame flues of the series H of the same heating wall. With this construction, each flame flue 17 communicates by a pair of ducts 23 and 24 or 25 and 25 with adjacent separate regenerators A, P, or P, A, and the flow through the several regenerators of a group K or L is maintained concurrently in the same direction, that is to say all three regenerators of a group are either operating for inflow or for outflow.

In the present embodiment of the invention, both series of flame flues G, H, of each heating wall 11 are either burning or operating for downflow to convey combustion products to the communicably connected regenerators beneath, and consequently the regenerators aligned on opposite sides of the central longitudinal partition 19 operate concurrently for flow in the same direction and in the same manner. The reversal in flow through the flame flues 17 on opposite sides of the coking chamber, and their communicably connected regenerators, may thus be said to take place longitudinally of the oven battery, instead of transversely thereof as has heretofore been a common practice in this art. The reversal of the oven is effected at the end of an operating period determined by practice, and by means of any preferred type of reversing mechanism. The function of such reversal is as follows: The regenerators that, prior to the reversal, operated as inflow regenerators become outflow regenerators, and the outflow operating regenerators become inflow operating regenerators; the two upburning series of flues switch function with the two downburning series of flues of the next adjacent heating wall, and the supply of gas is turned off from the previously upburning flues and turned on into the mains of the previously downburning flues.

Each flame flue 17 of both series of each heating wall has at its top a port or opening 26 for draft and the passage of combustion products or waste gas from the flame within the flue. The ports 24 of the respective series G and H of each heating wall open into horizontal or bus flues 27 and 28, companion to said series G and H, and connecting all of the vertical flues that communicate with such horizontal flues 27 and 28 by means of the ports 26. According to the invention, there are in each heating wall, and for each series of flues, a plurality of, in the present instance two of, such horizontal flues 27 or 28, positioned end to end with respect to each other, and respectively located on opposite

sides of the central dividing line L. By reason of the fact that there is a plurality of such horizontal flues 27, 28, these flues are not required to be of so great capacity as that necessary in present practice, and consequently the cross-sectional area of each horizontal flue 25 may be reduced, with the result that the thickness and strength of the heating walls are substantially increased in the region of the horizontal flues. Moreover, because of the fact that each horizontal flue communicates with a substantially reduced number of vertical flues, in the present instance half of the flues of each series, uniformly in distribution of flow through the vertical flues and the communicating regenerators is greatly promoted.

As shown in Fig. 3, each horizontal flue, 27 or 28, tapers from its middle toward its opposite ends in such manner that the smallest cross-sectional areas are located at its opposite extremities. The tapering channel thus formed serves to distribute the flow equally through the several vertical flues 17 with which such channel communicates. As shown, the two pairs of horizontal flues 27, 28, of each heating wall are communicably connected by means of passageways 29, respectively, with the pairs of corresponding horizontal flues 27, 28, of one of the next adjacent heating walls. These passageways or channels 29 are preferably lined at top and bottom, as shown in Fig. 2, with insulating material, such as Sil-o-cel or asbestos insulation, and preferably open up into substantially the middle portions of their respective connected pairs of flues 27, 28, as shown in Fig. 3, and extend longitudinally of the oven battery as shown in Fig. 2. Thus the entire flow from both series G and H of flues of the heating wall, within the flues of which combustion is being maintained, passes into and downwardly through both series of flues of the next adjacent heating walls, and each reversal operation is accompanied by a reversal in direction in flow of all of the flues of each heating wall. The draft through the ports 26 may be regulated by means of the usual movable dampers or sliding bricks 30 positioned in the ordinary way in the bottoms of the horizontal flues 27, 28, and adapted to be reached by the access flues 31 which extend from the top of the horizontal flues 27, 28, in each heating wall, to the top 15 of the oven battery, there being an access flue positioned over each flame or combustion flue of each heating wall.

Extending crosswise of the battery in each pillar wall 13, and located beneath the series of flues G or H thereabove, is a pair of gas supply channels 32 and 33. These channels 32 and 33 are for the purpose of supplying coke oven gas to the several flame flues of series on each side of the central line L, and,

to accomplish this end, the two pairs of channels 32, 33, that are companioned to each heating wall, respectively, to communicate with the individual flues 17 by means of ducts 34 that lead from such channels individually into the bottoms of the individual flues, as shown in Fig. 3. Within the several ducts are disposed the usual nozzles 35. The supply of gas to the respective pairs of channels 32 and 33 is derived from coke oven gas mains of the usual type and respectively located on the opposite sides of the battery and extending longitudinally therewith. Suitable means is provided for admitting or cutting off of gas with respect to both pairs of channels 32 and 33, with respect to each heating wall, it being understood that the gas supply is concurrently turned on in each pair of such channels or concurrently cut off from each pair of such channels.

For operating the battery alternatively with the use of a special generator gas, such as producer gas as a fuel, the several regenerators P, when operated for inflow, may be optionally connected with a producer gas main by a mechanism such as is disclosed in my co-pending application for patent for a coking retort oven, filed April 23, 1920, Serial Number 376,126, Patent No. 1,416,822, dated May 16, 1922, so that the producer gas may be directed into such of the regenerators P as are operating for inflow, and conveyed through these regenerators into burning flame flues of both series G and H.

The operation of the retort oven or battery when using a special generator gas, such as ordinary producer gas as a fuel, is as follows: The supply of coke oven gas to the coke oven gas main, and to all of the coke oven gas channels 32, 33, is cut off. A supply of producer gas is permitted to flow into the regenerator P of alternate groups, such as K, and passing through said regenerator is preheated before being delivered into the burning flame flues of both series G and H of alternate heating walls. During the inflow of producer gas through such regenerators of alternate groups K, waste gas from the downburning flues is flowing out through all of the regenerators of the groups L. In the regenerators A of the inflow operating groups K, inflow of air is maintained, which passing upwardly through such regenerators finally enters the burning flame flues of both series G and H, to support the combustion of the producer gas that is delivered thereto by the inflow operating regenerators P. On reversal of the flow, the inflow operating regenerators, comprising the groups K, all become outflow regenerators, and concurrently the outflow operating regenerators, comprising the groups L, all become inflow regenerators.

In operating the battery with coke oven

gas as fuel, the supply of producer gas to the regenerators P of alternate groups is shut off and air is permitted to flow into such regenerators in place of the producer gas. During coke oven gas operation a supply of coke oven gas is maintained in both pairs of channels 32 and 33 which feed the upburning flues. The reversing mechanism is operated at each reversal to place all of the inflow operating air regenerators in communication with the outer air, and concurrently all of the outflow operating regenerators in communication with the exhaust.

The invention disclosed in this application is a continuation in part of my prior application for Letters Patent in the United States for coking retort oven filed November 8, 1920, Serial 422,422, patent No. 1,374,546, issued April 12, 1921.

The invention as hereinabove set forth is embodied in a particular form of construction, but may be variously embodied within the scope of the claims hereinafter made.

I claim:

1. In a coking retort oven, in combination: a plurality of coking chambers; heating walls contiguous to such coking chambers and respectively constituted of two parallel series of vertical combustion flues; tapered horizontal flues in each heating wall and respectively connecting a plurality of the combustion flues of each series of their respective heating walls; the horizontal flues of both series of each heating wall being also communicably connected with the corresponding horizontal flues of an adjacent heating wall; individually regulable and individually reversible and crosswise-extending regenerators parallel lengthwise with the coking chamber and the heating walls, such regenerators being divided into groups of three regenerators each, two regenerators of each group being respectively communicably connected one with the flues of one series and the other with the flues of the other series of an adjacent heating wall, and the other regenerator of each group being connected with both flue-series of the adjacent heating wall; substantially as specified.

2. In a coking retort oven, in combination: a plurality of coking chambers; heating walls contiguous to such coking chambers and respectively constituted of two parallel series of vertical combustion flues; horizontal flues in each heating wall and respectively connecting a plurality of the combustion flues of each series of their respective heating walls; the horizontal flues of both series of each heating wall being also communicably connected with the corresponding horizontal flues of an adjacent heating wall; individually regulable and individually reversible and crosswise-extending regenerators parallel lengthwise

with the coking chamber and the heating walls, such regenerators being divided into groups of three regenerators each, two regenerators of each group being respectively communicably connected one with the flues of one series and the other with the flues of the other series of an adjacent heating wall, and the other regenerator of each group being connected with both flue-series of the adjacent heating wall; substantially as specified. 70 75

3. In a coking retort oven, in combination: a plurality of coking chambers; heating walls contiguous to such coking chambers and respectively constituted of two series of vertical combustion flues, a plurality of horizontal collecting flues in each heating wall and respectively connecting a plurality of the combustion flues of both series of their respective heating walls; the horizontal flues of both series being also communicably connected with the corresponding horizontal flues of both series of an adjacent heating wall; and regenerators communicating with said combustion flues; substantially as 80 85 90 specified.

4. In a coking retort oven, in combination: a plurality of coking chambers; heating walls contiguous to such coking chambers and respectively constituted of two series of vertical combustion flues operable reversibly for upflow and downflow; all of the combustion flues of both series of a heating wall being communicably connected with the combustion flues of both series of an adjacent heating wall; and crosswise-extending regenerators parallel lengthwise with the coking chamber and the heating wall, said regenerators communicating with such combustion flues; substantially as 95 100 105 specified.

5. In a coking retort oven, in combination: a plurality of coking chambers; heating walls contiguous to such coking chambers and respectively constituted of two parallel series of vertical combustion flues, communicably connected with both series of vertical combustion flues of an adjacent heating wall; and groups of regenerators, the groups being respectively communicably connected 110 115 with both series of such combustion flues of each heating wall; substantially as specified.

6. In a coking retort oven, in combination: a plurality of coking chambers; heating walls contiguous to such coking chambers and respectively constituted of two series of vertical combustion flues communicably connected with both series of combustion flues of an adjacent heating wall; and a reversible regenerative system, embodying gas and air regenerators communicably connected with both series of combustion flues of each heating wall, substantially as specified. 120 125

7. A coking retort oven having side-by-side coking chambers with intermediate flued 130

heating walls and reversible regenerators serving said flued walls and disposed in groups adapted respectively to serve alternately for inflow preheating of fuel gas and 5 air simultaneously and for concurrent waste-gas outflow, and the regenerators for inflow of fuel gas being separated from all the regenerators for concurrent outflow of waste-gas by intervening regenerators for inflow 10 of air, and having the heating walls operatively disposed in pairs, the two heating walls on the opposite sides of an intervening coking chamber constituting a separately functioning unit for the reversible regenerative 15 flow of the heating gases, the said two opposite walls being mutually interconnected with each other by duct means extending from wall to wall, so that all the gases produced by the combustion in the heating wall 20 on one side of said chamber are drawn off through only the heating wall on the other side of the same chamber.

8. In a coking retort oven battery, in combination: combustion chambers and communicably connected therewith a series of regenerators that is disposed longitudinally of the battery in groups respectively adapted to serve for inflow and outflow, the inflow 25 groups comprising regenerators for fuel gas 30 and regenerators for air on two opposite sides of said fuel gas regenerators, the regenerators for air being arranged next to the outflow regenerators and interposed between fuel gas regenerators and waste heat 35 regenerators, whereby counterflow between fuel gas and waste heat in regenerators alongside each other is prevented.

9. In a coking oven battery having a coke-side and a pusher-side, in combination: a 10 plurality of coking chambers extending from coke-side to pusher-side; heating walls contiguous to such coking chambers, each heating wall being constituted of coke-side and pusher-side series of combustion flues communicably connected with corresponding series of combustion flues in an adjacent heating wall; and coke-side and pusher-side regenerators respectively individual to and communicably connected with said series of 15 such combustion flues of each heating wall, whereby the control of the flow on the pusher-side may be effected separately from the control on the coke-side of the coking oven and said coke-side and said pusher-side regenerators being disposed in groups 20 adapted respectively to serve alternately for inflow preheating of fuel gas and air simultaneously and for concurrent waste-gas outflow, and the regenerators for inflow of fuel gas being separated from all the regenerators for concurrent outflow of waste-gas by intervening regenerators for inflow of air.

10. In combination with a coking chamber, flued heating walls respectively constituting the opposite side walls of said coking

chamber, the flues of the heating walls being disposed in groups communicably connected with each other by duct means extending across the coking chamber, reversible means for maintaining combustion in alternation 70 in said heating walls, the exhaust gases produced by the combustion in the groups of flues in one heating wall being drawn off through corresponding groups of flues in the other heating wall, and reversible regenerators respectively connected with said heating walls and disposed in groups adapted respectively to serve alternately for inflow preheating of fuel gas and air simultaneously and for concurrent waste-gas outflow, 75 and the regenerators for inflow of fuel gas being separated from all the regenerators for concurrent outflow of waste-gas by intervening regenerators for inflow of air; substantially as specified. 80

11. A coking retort oven battery of the cross regenerative type with ducts extending across the retorts and connecting the combustion flues of parallel heating walls, each heating wall having two parallel series 90 of vertical combustion flues in both of which the flow of the gases is simultaneously in the same direction, and which communicate with the similar series of flues in another heating wall by means of the cross-over ducts. 95

12. A coking retort oven as claimed in claim 11 having each flued heating wall connected to a group of three regenerators arranged side by side whereof the two outer regenerators communicate each with one of 100 the flue series while the middle regenerator communicates with both flue series.

13. A coking retort oven having coking chambers with flued heating walls connected by ducts extending across such coking chambers and having the flued heating walls constituted of series of flues and connected to groups of regenerators, each regenerator group having three regenerators arranged alongside each other whereof the two outer 110 regenerators communicate each with one flue series only while the middle regenerator communicates with two flue series, and the middle regenerator only of each group having connection with a source of fuel gas 115 supply. 125

14. A coking retort oven battery as claimed in claim 11 in which the combustion flues of one series lie in a row adjacent the retort at one side of the heating wall and the flues of the other series lie in a row adjacent the retort at the other side of the heating wall. 120

15. In combination with a coking chamber, flued heating walls respectively constituting the opposite side walls of said coking chamber, the flues in the heating walls being disposed in groups, the groups of flues of said heating walls being communicably connected with each other by duct means ex-

tending over the top of the coking chamber, reversible means for maintaining combustion in alternation in said heating walls, the exhaust gases produced by the combustion in 5 one heating wall being drawn off through the other, and reversible regenerators respectively connected with said heating walls and disposed in groups adapted respectively to serve alternately for inflow preheating of 10 fuel gas and air simultaneously and for concurrent waste-gas outflow, and the regenerators for inflow of fuel gas being separated from all the regenerators for concurrent outflow of waste-gas by intervening regenerators for inflow of air, substantially as specified.

16. In a coking retort oven, in combination: a plurality of parallel coking chambers; flued heating walls therefor and parallel therewith; duct means communicably connecting a plurality of such flued heating walls that are in different planes and that are adapted to operate as inflow heating walls with a plurality of such heating walls 25 that are in different planes and that are adapted to operate concurrently as outflow heating walls; and individually regulable regenerators arranged below and parallel with said heating walls and coking chambers and communicably connected with their respective flued heating walls and disposed in groups adapted to serve alternately for inflow of combustion media and outflow of waste gas, each group comprising at least 30 three regenerators.

17. Apparatus as claimed in claim 16, in which there is a series of such duct means.

18. In a coking retort oven, in combination: parallel coking chambers; a plurality 40 of series of vertical heating flues; each series of flues being parallel to said coking chambers and to each other; duct means communicably connecting a plurality of parallel series of heating flues that are adapted to operate for inflow with a plurality of parallel series of heating flues that are adapted to operate concurrently for outflow; individually regulable regenerators arranged below and parallel with said coking chambers and 45 said series of heating flues and communicably connected with their respective series of heating flues.

19. Apparatus as claimed in claim 18 in which there is a series of such duct means.

20. In a coking retort oven battery, in combination: combustion chambers and communicably connected therewith a series of regenerators arranged alongside each other and disposed in groups adapted respectively 55 to serve alternately for inflow preheating of fuel gas and air simultaneously and for concurrent waste-gas outflow, and the regenerators for inflow of fuel gas being separated from all the regenerators for concurrent outflow of waste-gas by intervening 60

regenerators for inflow of air on opposite sides of the fuel gas regenerators.

21. In a coking retort oven battery, in combination: a series of side-by-side coking-chambers with intermediate heating-walls 70 that extend transversely of the battery and series and contain heating-flues; and a series of side-by-side regenerators that extend transversely of the battery and series and are communicably connected with the flues 75 of said heating-walls, the series of regenerators being disposed in side-by-side groups adapted to serve in alternation for inflow preheating of fuel gas and air simultaneously and for concurrent waste-gas outflow, the 80 inflow groups alternating in position with the concurrent outflow groups and including air inflow regenerators that are interposed between the fuel-gas inflow regenerators and the concurrently adjacent outflow 85 groups of regenerators.

22. In a coking retort oven battery, in combination: a series of side-by-side coking-chambers with intermediate heating-walls 90 that extend transversely of the battery and series and contain heating-flues; and a series of side-by-side regenerators that extend transversely of the battery and series and are communicably connected with the flues 95 of said heating-walls, the series of regenerators being disposed in side-by-side groups adapted to serve in alternation for inflow preheating of fuel gas and air simultaneously and for concurrent waste-gas outflow, said groups comprising regenerative units of 100 at least three regenerators, the outer lateral regenerators of each of said units being adapted for air inflow and at least one intermediate regenerator of each of said units being adapted for fuel gas inflow.

23. In a coking retort oven battery, the combination claimed in claim 22 and in which the groups of regenerators, comprising regenerative units of at least three regenerators, are so disposed that a fuel-gas regenerator of each of said units is communicably connected with two sets of heating-flues and its outer lateral air regenerators are each communicably connected with one of said sets of heating-flues.

24. In a coking retort oven battery, in combination: a series of side-by-side coking-chambers with intermediate heating-walls that extend transversely of the battery and series and contain series of heating-flues, the heating-flue series being parallel with each other and with the sides of the coking-chambers; duct means communicably connecting, for concurrently reverse flow, a plurality of parallel series of heating-flues on one side of a coking chamber with a plurality of parallel series of heating-flues on the other side of said coking-chamber; and a series of side-by-side regenerators that extend transversely of the bat- 120 125 130

tery and series and are communicably connected with the series of heating-flues, the series of regenerators being disposed in side-by-side groups adapted to serve in alternation for preheating the inflow to and receiving the outflow from the pluralities of heating-flue series that concurrently have reverse flow on the one and the other side of a coking chamber, each group comprising at least three regenerators.

25. In a coking retort oven battery, in combination: a series of side-by-side coking-chambers with intermediate heating-walls that extend transversely of the battery and series and contain heating-flues; and a series of side-by-side regenerators that extend transversely of the battery and series and are communicably connected with the flues of said heating-walls, the series of regenerators being disposed in side-by-side groups adapted to serve in alternation for inflow preheating of fuel gas and air simultaneously and for concurrent waste-gas outflow, said groups comprising regenerative units of at least three contiguous regenerators, the outer lateral regenerators of each of said units being adapted for inflow of one of said combustion media and at least one intermediate regenerator of each of said units being adapted for inflow of the other of said combustion media; fuel-gas regenerators being substantially more isolated from all adjacent waste-gas regenerators than from adjacent air-regenerators.

26. In a coking retort oven battery, the combination claimed in claim 25 and in which the groups of regenerators, comprising regenerative units of three regenerators, are so disposed that the fuel-gas regenerator of each of said units is communicably connected with two sets of heating-flues and its outer lateral air regenerators are each com-

municably connected with one of said sets of heating-flues.

27. In a coking retort oven battery, in combination: a series of side-by-side coking-chambers with intermediate heating-walls that extend transversely of the battery and series and contain heating-flues; and a series of side-by-side regenerators that extend transversely of the battery and series and are communicably connected with the flues of said heating-walls, said series of regenerators being disposed in side-by-side groups adapted to serve in alternation for inflow preheating of fuel gas and air simultaneously and for concurrent waste-gas outflow, said groups comprising regenerative units of at least three contiguous regenerators, the outer lateral regenerators of each of said units being adapted for inflow of one of said combustion media and at least one intermediate regenerator of each of said units being adapted for inflow of the other of said combustion media; fuel-gas regenerators being substantially more isolated from all adjacent waste-gas regenerators than from adjacent air-regenerators.

28. In a coking retort oven battery, the combination claimed in claim 27 and in which the regenerative units are of three regenerators comprising one lateral regenerator that communicates with certain heating-flues and one lateral regenerator that communicates with certain other heating flues and an intermediate larger regenerator that communicates with the heating-flues served by both of the lateral regenerators.

JOSEPH BECKER.
